UNITED STATES PATENT OFFICE

157,563

COMBINATION ELECTRIC RANGE AND RADIO

George E. Bromley, Fredonia, Pa.

Application April 21, 1949, Serial No. 2,181

Term of patent 14 years

(Cl. D81—4)

To all whom it may concern:

Be it known that I, George E. Bromley, a citizen of the United States, residing at Fredonia, in the county of Mercer and State of Pennsylvania, have invented a new, original, and ornamental Design for a Combination Electric Range and Radio, of which the following is a specification, reference being had to the accompanying drawing, forming part thereof.

Figure 1 is a perspective view of a combination electric range and radio showing my new design, and

Figure 2 is a top plan view thereof.

I claim:

The ornamental design for a combination electric range and radio, as shown.

GEORGE E. BROMLEY.
